UNITED STATES PATENT OFFICE.

NILS AUGUST WAHLQUIST, OF CHICAGO, ILLINOIS.

NECKTIE.

Application filed January 16, 1924. Serial No. 686,470.

To all whom it may concern.

Be it known that I, NILS AUGUST WAHLQUIST, a citizen of the United States, residing at Chicago, in the county of Cook, State 5 of Illinois, have invented certain new and useful Improvements in Neckties, of which the following is a specification, reference being had to the accompanying drawings, forming a part thereof.

10 The purpose of this invention is to provide a "slip easy" tie, that is, a tie which may be drawn between the folds of a collar with which it is to be worn without undue stress upon the tie and which may, therefore, be 15 readily adjusted properly at the opening of the collar in the process, or after the process, of tying. It consists in the elements and features of construction shown and described as indicated in the claims.

20 In the drawings:—

Figure 1 is a view of a tie equipped with this invention showing the inner side thereof at the middle part of the length where the devices which characterize the invention 25 are mounted.

Figure 2 is a perspective view of one of the clips which characterizes the invention.

Figure 3 is a section at the line 3—3 on Figure 2.

30 Figure 4 is a section at the line 4—4 on Figure 1.

The body of the tie shown in the drawings is assumed to be made of fabric folded and seamed in tubular or double ply form 35 and at the middle portion of its length where it is embraced between the folds of the collar. The means for rendering the tie easy to slip between the folds of the collar by which it is embraced, consists of a plurality of clips, B, made of metal polished on the outer side, said clip being struck from sheet metal and desirably slightly convex on the outer polished side. The convexity which will normally result from striking 40

45 such clips from the suitable thin sheet metal is, in most cases, sufficient for the purpose for which the convexity is desirable, which is to reduce to a minimum the area of contact of the clip with the collar band. These 50 clips are provided with a plurality of tangs extending from the margin at the concave side for penetrating the fabric of the tie

and being clinched therein or thereon. These tangs, B¹, are acute-pointed, as seen at b¹ and their acute terminals are desirably slightly flexed inward, as may be noted from Figure 2, so that when the tie is lodged upon a hard platen for receiving the clips, and the clips are applied for engaging their tang terminals with the inner side of the tie, are struck for forcing the tangs into the fabric of the tie and clinching, these tangs, are normally deflected inward in the proper direction for clinching; and when the tie is of two-ply or tubular construction mentioned 65 and shown, the inwardly curved acute terminals will usually be clinched between the two layers of the fabric, that is, against the inner side of the layer upon which they were applied, said layer being at the inner side 70 of the tie, so that the tangs do not appear at all at the outer side of the tie.

I do not limit myself to any specific form or contour for these clips; but I have ascertained experimentally that the most desirable form is oblong rather than round or square and that a relatively narrow oblong clip is preferable to one which has its two dimensions more nearly equal. Also for the purpose of causing the tie to slip properly 75 between the folds of the collar and be drawn up into the fold rather than down out of it, the oblong clips should be mounted on the tie as shown in the drawings,—with the longer dimension obliquely crosswise at an 80 angle of about 45 degrees to the length of the tie and sloping from lower toward the upper edge onward in the direction in which the tie is to be drawn through the collar, that is, in the case of a four-in-hand tie, upward and onward toward the end of the tie which is first inserted and pulled for drawing the tie in place, this being what is commonly referred to as the shorter end of 85 a four-in-hand tie.

90 I claim:—

1. A necktie and the like having polished slightly convex clips of hard material clinched to the fabric of the tie at the inner side, positioned at intervals over the portion 100 of the length of the tie which is to be embraced between the folds of the collar at the rear portion thereof.

2. In the construction as defined in claim

1, foregoing, the clips being oblong with their longer dimension extending obliquely with respect to the length of the tie.

3. In the construction defined in claim 1, 5 foregoing, the clips being oblong and mounted on the tie with their longer dimension at an angle of substantially 45° to the

length of the tie and at the middle part of the width thereof.

In testimony whereof, I have hereunto set 10 my hand at Chicago, Illinois, this 11th day of January, 1924.

NILS AUGUST WAHLQUIST.
